UNITED STATES PATENT OFFICE.

WILMER M. SHALLCROSS, OF MILWAUKEE, WISCONSIN, ASSIGNOR TO SHALLCROSS CONTROL SYSTEMS CO., OF MILWAUKEE, WISCONSIN, A CORPORATION OF WISCONSIN.

COKE-PRODUCING-OVEN REGULATOR.

Application filed September 27, 1922. Serial No. 530,890.

This invention relates to certain new and useful improvements in coke producing ovens and refers more particularly to a regulator therefor.

5 All coke producing ovens may be said to broadly consist of a heating chamber surrounding a coking retort, the heating chamber being heated either by burning therein of coke or gases, the gases given off by the coke being formed being conveyed to a place of storage through a "hydraulic main."

The burnt gases are conducted from the oven through devices designed to usefully extract the heat therefrom and are finally 15 led through a conduit or duct preferably disposed under the ground to an ordinary stack through which they are expelled at as cool a temperature as possible.

In gas ovens it is highly important that 20 the flow of burnt gases through the exhaust conduit to the stack, and consequently the pressure therein, be maintained substantially uniform to prevent back pressure in the heating chamber and the consequent 25 seepage of the burnt gases through the porous brick walls of the retort and the resultant dilution of the pure gases given off by the coke being formed. The uniform pressure maintained on the exhaust gases is also 30 a material aid toward maintaining uniform temperatures in the heating chamber.

Heretofore the control of the flow through the exhaust conduit has been manual, i. e., a valve within the conduit is set 35 at an approximately correct position and maintained at this adjustment. This procedure results in a loss of gas produced and under manual regulation of the gas of a coke oven in which the heating chamber 40 temperature is maintained by the gas produced in the coke retort there is approximately 60% surplus gas which is generally sold commercially and 40% of gas employed in maintaining the temperature of the 45 heating chamber. Experience has proven that with automatic regulation, and the consequent maintenance of the pressure in the conduit at a substantially uniform degree, the surplus gas is materially increased and 50 the amount required for maintaining the temperature of the heating chamber is much less, resulting in a considerable saving over the manual regulation, which is of tremendous importance in the commercial field.

55 Therefore, having the above in mind it

is a primary object of this invention to provide means for maintaining the flow of burnt gas through the exhaust conduit substantially uniform, and consequently the pressure therein substantially constant. 60

It is another object of this invention to speed up and facilitate the automatic regulation of the valve member controlling the rate of flow of burnt gases through the conduit by varying the speed of the valve 65 member actuating motor in proportion to the change of pressure to be corrected.

It is another object of this invention to provide means for visually indicating when the valve actuating motor is at rest, and 70 when it is operating in either forward or reverse and at what speed.

It is a further object of this invention to provide a motor actuated valve for controlling the rate of flow of burnt gases 75 through the exhaust conduit and maintaining the same substantially uniform having float means for controlling the same, which float means is controlled by pressure from the conduit. 80

A further object of this invention resides in the provision of an improved type of control for the valve actuating motor having means for indicating the pressure maintained within the conduit. 85

And a still further object of this invention resides in the provision of an improved control for the valve actuating motor in which the float proper is suspended within the pontoon chamber by a spring member. 90

With the above and other objects in view which will appear as the description proceeds, my invention resides in the novel construction, combination and arrangement of parts substantially as hereinafter described 95 and more particularly defined by the appended claims, it being understood that such changes in the precise embodiment of the herein disclosed invention may be made as come within the scope of the claims. 100

In the accompanying drawings, I have illustrated one complete example of the physical embodiment of my invention constructed according to the best mode I have so far devised for the practical application 105 of the principles thereof, and in which:—

Figure 1 is a diagrammatic illustration of a coke plant, parts thereof being broken away and in section;

Figure 2 is a diagram of the circuits em- 110

ployed in connection with my improved control;

Figure 3 is a view taken through the transmission box for connecting the valve member actuating motor with the valve on the plane of the line 3—3 of Figure 4;

Figure 4 is a view partly in section and partly in elevation taken transversely through Figure 3 on the plane of line 10 4—4, and

Figure 5 is a view partly in section and partly in elevation of the control for the valve member actuating motor.

Referring now more particularly to the accompanying drawings in which like numerals designate like parts throughout the several views, numeral 6 designates a coke oven including a coke retort 7, a heating chamber or chambers 8 surrounding the same, a duct 9 connecting the coke retort with a hydraulic main 10 through which the released gases given off by the coke being formed is conveyed prior to having the valuable contents thereof extracted and the 25 gas remaining divided in two parts, one part of which is stored for commercial purposes and the other reconducted to the heating chamber where it is burnt, and 11 designates a duct or conduit connecting the 30 heating chamber 8 with a stack 12 to which the burnt gases are conveyed after they have previously been passed through boilers or regenerators to extract the heat therefrom, duct 11 being preferably disposed under 35 the ground. It is highly essential that the rate at which the burnt gases are expelled from the heating chamber through duct 11 and at stack 12 be maintained uniform and at a degree which will prevent back pressure in the heating chamber and the consequent seepage through the walls of the retort of the burnt gases resulting in the dilution of the gases produced by the roasting of the coke, or the lack of insufficient pressure in the heating chamber and the consequent seepage through the walls of the retort of the gases generated therein and the consequent loss thereof.

In other words, it is essential that the 50 pressure within the retort and within the heating chamber be balanced and that advantage is accomplished by means of regulation of the flow of gases from the retort by means not shown and the control of the 55 flow of burnt gases from the heating chamber by the means hereinafter described.

Positioned within duct 11 at some position between the heating chamber and the stack 12 is a valve member 13 which is movable to and from a closed position and in this invention the valve member is mounted on a shaft 14 which is connected with a shaft 15 driven through reduction gearing hereinafter described by a motor 16. The 60 reduction gearing and motor 16 are mounted

in a casing 17 and consist of a vertically journaled shaft 18 having its lower end connected by a universal coupling with shaft 15 and its upper end mounting a larger beveled gear 20 with which is meshed a drive pinion 21 carried by the outer end of a shaft 22 on which is intermediately mounted a worm wheel 23. Worm wheel 23 is engaged by a worm 24 mounted on a shaft 25 journaled in an inner housing 26 and having thereon, adjacent one end, a worm wheel 27 with which is meshed a worm 28 mounted on a shaft 29 extended outwardly of casing 26 and connected with motor 16 by a coupling 30. By enclosing the worm wheels in casing 26, the same run in oil to thus insure efficient operation.

Motor 16 is controlled to run either forward or reverse at a speed proportionate to the change in pressure to be corrected by a pontoon switch unit designated generally as at 31 and consisting of a casing 32 having an intermediate partition or wall 33 therein on the upper face of which is formed an annular rib 34 to define an annular water chamber 35 in which is suspended the depending flange 36 of the gasometer 37. The depending flange of the float is preferably tubular to provide a dampening effect and the lower portion thereof is disposed beneath the level of the liquid within chamber 35 to prevent the passage of gas from the space 39 between the gasometer and the rib 34 to the space between the flange and the casing 32 proper.

As illustrated in Figure 5, an inlet 40 communicates with the space between the annular rib 34 and is connected with the interior of duct 11 at a point between the valve member and the heating oven by a conduit 41 so that the float is influenced by the pressure in the duct inwardly of valve 13. To insure absolute accuracy, the gasometer is suspended and supported by a spring 42 concealed within a tube 43 communicating with casing 32 substantially in alignment with the axis of the annular rib 34 and the lower end of the spring is connected centrally with the gasometer by passing through an opening in the end 44 of a bell crank lever 45 to be later described, which is in turn connected with the spring the upper end of which is connected as at 46 to an adjustable post or screw 47. Screw 47 passes outwardly of tube 43 through a cap or cover 48 closing the end thereof and has a knurled nut and adjusting wheel 49 for moving the same into and out of the tube 43 to regulate the pressure maintained within duct 11.

In order that the device may be actually set for operation at any desired pressure, a pointer or finger 50 is carried by post 47 which cooperates with suitable graduations 51 on the exterior of tube 43, as clearly de-

picted in Figure 5. As will be obvious, as post 47 is adjusted to vary the pressure at which motor 16 is actuated, pointer 50 is carried thereby to the proper designation.

5 Mounted on the casing 32 is a panel board 52 carrying a central contact 53 having two contact faces and two outer contacts 54 and 55 adapted to be electrically connected with contacts 56 and 57, respectively, which are 10 also engageable with the center contact 53 and which are carried by levers 58 and 59 freely journaled on a shaft 60. Contacts 56 and 57 are normally yieldably urged to engagement with the opposed faces of the central contact 53 by a spring 61 the ends of which are connected with the levers 58 and 59, an adjusting screw 62 being provided to vary the tension thereof, and arms 58 and 59 are selectively movable to disengage the 20 contacts carried thereby from the center contact 53 and to, should the conditions within the duct 11 warrant it, engage the contact carried thereby with the adjacent outer contact.

25 This movement of the levers 58 and 59 is effected by arm 63 of bell crank lever 45, the the other end of which is normally disposed between adjustable stops 64 and 65 carried by levers 58 and 59 so that a lowering movement of the gasometer by reason of a fall of 30 the pressure within the conduit 11 below the desired degree will move the bell crank arm 63 to the left with reference to Figure 5 and disengage contact 56 from contact 53 to thus run motor 16 at a slow speed in the direction necessary to move valve member 35 13 toward closed position and should the pressure be considerably below normal, the speed of the motor is increased by the continued fall of the float until contacts 54 and 40 56 engage.

In Figure 2 is illustrated a diagram of the 45 circuits employed in connection with the contacts carried by the panel board 52 and in which the numeral 66 designates the positive line and numeral 67 the negative having a shunt field 68 connected thereacross and leading from the positive line to the center contact 53 is a conductor 69 in which is positioned a limit switch 70, contacts 56 and 57 being connected with the armature of the motor by conductors 71 and 72, respectively. Connected across conductor 71 and negative line 67 is a conductor 73 having therein suitable resistance 74 from which leads, at an intermediate point, a conductor 75 which passes through a lamp 76 and is again connected with conductor 73. Connected across conductor 72 and negative line 67 is a conductor 77 having a suitable resistance 78 therein from which leads, at an intermediate point, a conductor 79 which passes through a lamp 80 and is connected with conductor 77. With this wiring, when the parts are in 60 65 the position illustrated in Figures 2 and

5, the motor circuit is open at contacts 54 and 56, and 55 and 57, the armature 16 is dynamically braked by reason of the shunt field being energized and the armature being short circuited through the circuit established from the armature, through conductor 71, contacts 56, 53 and 57 and back to the other side of the armature through conductor 72, and lights 76 and 80 burn at full brilliancy by reason of the current flowing therethrough from the positive line to the negative line, as will be readily apparent.

In the event the pressure within the duct falls below the set degree and contacts 53 and 56 separate, as hereinbefore described, the motor is then slowly operated in the direction to close valve 13 by reason of the current flowing from the positive line through contacts 53, 57, conductor 72, through the armature of the motor, conductor 71, resistance 74 and to the negative line 67 through conductor 73 as a result of which light 76 burns at half brilliancy and light 80 remains at full brilliancy.

As the gasometer moves, opening contacts 53 and 56 the motor does not come up to its low speed suddenly. As the gasometer lever 63 touches the screw 64 of lever 58 the motor starts at an extremely low speed due to the slight relieving of the pressure between the graphite contacts 53 and 56. As the gasometer lever 63 presses harder against contact lever 58 the motor runs faster, until the contacts are actually separated when the motor is running at a uniform low speed. Between 0 and "low speed" therefore the motor runs at a speed roughly proportional to the change in pressure in the conduit which is to be corrected.

However, a continued movement to the left with reference to Figure 5 of contact 56 until contact 56 engages contact 54 will cause the motor speed to increase by reason of the resistance 74 being cut out and the current then flowing through the armature, conductor 71, contacts 56 and 54, and to the negative line 67 through a conductor 81. As the condition within the conduit approaches normal, the gasometer rises moving bell crank lever arm 63 to the right with reference to Figure 5 and consequently permitting corresponding movement of contact 56 and as contacts 56 and 54 disengage, the resistance 74 is again cut in and the motor speed reduced and as the condition within the conduit again reaches normal, contacts 56 and 53 engage, dynamically breaking the same as above described to effect the abrupt arresting of the rotation thereof.

In the event the pressure within the conduit increases beyond the normal degree, the gasometer is raised, causing bell crank lever arm 63 to disengage contacts 53 and 57, as a result of which the current through the motor armature is reversed, being then from

the positive line through contacts 53 and 56, conductor 71, through the armature, conductor 72, resistance 78 and to the negative line 67 through the conductor 77, lamp 80 being in parallel with the resistance burning at half brilliancy. Upon the continued movement to the right with reference to Figure 5 of the contact 57 under influence of the gasometer, an engagement of contact 57 with contact 55 will cut out resistance 78 and increase the motor speed, the current flowing from the armature through conductor 72, contacts 57 and 55 and out to negative line 67, through a conductor 82. As the pressure within the conduit falls, float 37 returns when the operation of the motor is substantially the same as that when the movement of the float 37 reverses after contacts 54 and 56 have been engaged.

20 20 What I claim as my invention is:—

1. In a coke oven, the combination with a heating chamber, means for heating the chamber and a conduit connecting the heating chamber with a stack for conducting burnt gases from the chamber, of a valve member for controlling the flow of gases through the conduit, a variable speed motor connected with the valve member to move the same to and from closed position to regulate the flow of burnt gases through the conduit, and consequently the pressure therein, a source of power connectable with the motor to actuate the same and move the valve member, a gasometer controlled by pressure from the conduit, and means actuated by movement of the gasometer from a normal position by reason of a change in the conduit pressure from a predetermined degree to connect the motor with its source

of power, the speed of the motor varying 40 in proportion to the degree of movement of the gasometer.

2. In an apparatus of the character described, a gas conveying conduit, a valve member therein for controlling the flow of gas through the conduit and consequently the pressure therein, a motor for actuating the valve member and means for actuating the motor at a speed in proportion to the change of pressure in the conduit to be 50 corrected.

3. A control of the character described comprising a gasometer, motor controlling mechanism actuated by the gasometer, spring means for suspending the gasometer, 55 and means for adjusting the tension of the spring means whereby the operation of the gasometer may be readily regulated.

4. A control of the character described comprising a gasometer, motor controlling mechanism actuated by the gasometer, spring means for suspending the gasometer, means for adjusting the tension of the spring means whereby the operation of the gasometer may be readily regulated, and 60 means for indicating the degree at which the control is regulated to operate.

5. In a control of the character described, a gasometer, motor control means connected therewith and operable by actuation of the gasometer under a variance in pressure beyond a predetermined degree, means for adjusting the degree at which the gasometer actuates the motor control, and means for indicating the pressure at which the gasometer is set to actuate the motor control. 70

In testimony whereof I affix my signature.

WILMER M. SHALLCROSS.
